CHARLES S. PALMER, OF PITTSBURGH, PENNSYLVANIA.

PROCESS OF MAKING BY-PRODUCTS FROM INACTIVE AND INERT OILS OR GASES.

Application filed September 28, 1921. Serial No. 503,901.

Most natural hydrocarbon oils and gases are inactive in their chemical nature so that they will not only pass through ordinary acids, alkalies and salts without reaction, but they will also stand a considerable degree of heat, even if mixed with some air or oxygen, without ignition or burning or oxidation.

One of the exception to this, and frequently 10 a point of attack, is the use of chlorine, or one of the other halogens is used for attacking of paraffines, but owing to the high cost of chlorine—as compared with the free oxygen of the atmosphere—and also the fact 15 that the product obtained is frequently inactive, the chlorine method is frequently made impracticable.

In considering the problem of the oxidation of the paraffines it should be noted primarily 20 that the general purpose is a favorable one, because it is exothermic, that is, oxidation of the paraffines or related hydrocarbons means the giving off of a great amount of heat; and this means that the general processes of oxidizing the paraffines may be compared in 25 their relations to natural physical economies and possibilities to the rolling of rocks down hill,—not up hill.

To carry on this figure of rolling rocks 30 down hill as an illustration in showing the obvious possibility of oxidizing the paraffines, after the oxidation or burning is once started by the proper "ignition", one may say that the chemical engineer is in the 35 position of those at the top of a precipice who would roll rocks down hill. But, note that these rocks must be rolled to the edge of the precipice, and there is also a slight elevation, or ridge, or hump, over which 40 they must be rolled. After they are once lifted over this ridge (which represents ignition) they will themselves roll down hill to the bottom, provided they are supplied with the requisite amount of oxygen for their complete combustion. But it is the trick, or the 45 uniqueness of the chemistry of the paraffines and their related hydrocarbons, that they frequently require special conditions and devices to be started over the hill edge hump on this down hill rolling of oxidation.

Much experience, observation and experimentation for many years has shown me that while the ordinary paraffines are quite inert, and their ignition is controlled with difficulty,—even under apparently favorable

circumstances—yet, many related hydrocarbon compounds—notably those of the various "unsaturated" series—lend themselves more easily to ignition, burning or oxidation. Now, these so-called "unsaturated" hydrocarbons, which are more or less active chemically, can be obtained readily from the inactive paraffine hydrocarbons, as by cracking; and this process of cracking the paraffines seems to be a promising preliminary treatment for changing the inactive paraffine hydrocarbons into such active hydrocarbons as can be more readily ignited or oxidized.

Once having changed the inactive paraffine hydrocarbons and the less active "unsaturated" hydrocarbons into more active hydrocarbons, the next step is to mix them with the right quantity of air or oxygen for the desired degree of oxidation. This air or oxygen may, of course, be preheated to assist in the oxidation or burning.

The next step after changing the inactive or partially active hydrocarbons into more active hydrocarbons,—as by cracking—is, of course, to start the oxidation ball rolling down hill, as by suitable "ignition", and this oxidation or burning of the mixed active hydrocarbons and oxygen or air is carried on in a suitable "igniter".

Having thus specified some of the objects and salient features of the present invention I will now proceed to describe the same with reference to the accompanying drawings illustrating several apparatus such as may be used for carrying out the invention, and in which drawings—

Figs. 1 and 2 illustrate suitable apparatus, more or less diagrammatic; Fig. 2 being a continuation of Fig. 1 to show a complete apparatus; and

Fig. 3 illustrates a modification.

Fig. 4 is a process diagram which is illustrative and explanatory of the process involved herein.

Referring to Fig. 1, a reservoir 10 is provided for the oil, which is supplied by a discharge nozzle 11. It will be obvious to those skilled in the art how vapors, with their metering, may be supplied in the first instance instead of oil. The oil reservoir 10 is provided with a discharge nozzle 12 controlled by regulating-valve 13, there being a sight gauge 14 introduced between the nozzle 12 and a pipe 15. The oil may be regulated

in drops by the valve 13, and these are visible through the sight gauge 14.

Supply pipe 15 leads to a retort 16 constituting a cracker, which may be heated by any suitable means, as from a burner 17. The vapors of the oil, gas, etc., introduced into the cracker 16 are broken up or cracked preferably through the employment of suitable catalytics, as for example, the catalytic may be in the form of confined sheets 18 of wire cloth, as of Monel metal.

The catalytic employed in the cracking chamber is not necessarily limited to Monel metal, (which is illustrated). I have found that other metals, such as iron, nickel, copper, chromium or other alloys, or alloys of related elements may be used as catalytics and are very efficient in promoting cracking.

The cracking chamber 16 is connected by a pipe 19 with a mixing chamber 20, which is provided with suitable interior perforated or reticulated elements or the like 21, as mixing baffles, for the purpose of facilitating admixture of oxygen, as, for instance, that contained in the atmosphere with the vapors emanating from the cracking chamber 16. Air pipe 24 is connected with a coil 23 constituting a preheater, and such air may be supplied by means of an air compressor 25 at one end of pipe 24 between which compressor and the inlet end of coil 23 a suitable meter 26 is arranged. The compressed air is preheated in the coil 23 by reason of the fact that it is enclosed in a heating chamber 22, which likewise contains the cracking chamber 16 and the burner 17. One end of the preheating coil 23 is connected with the vapor inlet end of the mixing chamber 20, and the other end of the pipe 24 between the inlet end of the preheating coil of the oil reservoir 10 constitutes means for introducing air pressure over the body of oil in the reservoir 10 so as to prevent back pressure from lifting the oil in feeding.

A pipe 28 connects that end of the mixing chamber from which the commingled vaporized oil or the gas is conducted, together with the admixed air, to an igniting chamber 29, which preferably contains an activating or catalytic filling 30, preferably of such materials as iron, copper, "platinized asbestos", "vanadium asbestos", etc., to assist in ignition or oxidation, and at temperatures preferably between 300° centigrade as a lower limit, and 700° centigrade as an upper limit. The igniting chamber 30 and its contents are kept moderately hot by means of a burner 31.

Heating means may be used as part of the apparatus and are here shown as a chamber 32 provided with headers 33, 34 for tubes 35 which pass through the chamber 32, it being possible to use this heat control by employing the latent heat of the vaporization of hot water. The ignited mixture is conducted from the igniting chamber 30 by a pipe 36

to the header 34 and the mixed gases, etc. pass down through the tubes 35 to the header 33 and out at a discharge pipe 37. An accessory circulating pump may be used. The heat control means are preferably regulated in any suitable way, as by means of a water-circulating device 38 for containing boiling hot, or cold water, the same being connected to the lower end of the chamber 32 by a pipe 39, and with the upper end thereof by means of a pipe 40. The pipes 39 and 40 are preferably controlled by means of hand-operated valves 41, 42. Steam may be led from the steam-space of the chamber 32 by means of an outlet pipe 43 through a meter 45, and from thence through a pipe 46 controlled by a valve 47 to the pipe 28 which connects the mixing chamber 20 with the igniter 29. Pipe 43 is preferably controlled by a valve 44 just ahead of the meter 45. A valved steam-pipe 43a may supply steam independently of, or with, the heat-control means 32, etc.

It will be seen that so far as described the ignition in igniting chamber 29 of the ordinary paraffines, after being cracked, is rendered favorable by such previous cracking, and that this applies not only to ordinary paraffines which are quite inert, but to many related hydrocarbon compounds, so that oxidation by ignition in the igniter 29 is rendered possible.

In the process of oxidizing the cracked oils by oxygen or the hot oxygen of the air in the mixing chamber 20 and the igniter 29, the action of steam, whether saturated or superheated, is a possibility under the present process.

I have found as a result of many experiments on parallel attempts to get carbon black by burning gases that the introduction of steam into the mixture of gas and air had a remarkable effect on the nature and combustion of the flame; so that, for instance, by the action and presence of steam a very smoky flame can be changed instantly through all the graduations from a sooty flame to a bright, sootless flame. It will be noted that this action is the burning of gases and heavy vapors in the open air where there is an abundance of oxygen.

Acting on this analogy, one might suppose that the action of steam in the apparatus and process herein described, on the burning of cracked hydrocarbons in the igniter, would promote extreme oxidation (with a production of CO_2 , which here is not wanted, as it means "rolling the rocks to the bottom of the hill" and a waste both of chemical products and energy, in that the carbon compounds burn to CO_2); but I found that the action of steam on the igniter, under the conditions of the apparatus and process used, was not to produce extreme oxidation, giving CO_2 , but a modified oxidation, producing the aldehydes, and possibly some of the aldehyde-

alcohols or alcohols. Of course, it is obvious that this apparatus and process aims to produce materials and products of limited oxidation, not complete oxidation, (to CO_2), and results involving unnecessary waste.

This action of steam also in this apparatus and process is useful not only in promoting and controlling the oxidation, but also in gathering up the condensed aldehyde compounds,—and possibly, some related compounds—in the condensed water which comes from the steam. Of course, there is some water produced in the oxidation without the introduction of steam. Also, the range of plain saturated steam and superheated steam are different, and vary with the original "oil" or gas used, and also, with the degree and kind of cracking, not to ignore also the variation with the action of specific catalytics. I do not limit myself to any particular side of this.

In Fig. 1 a partial supply of steam is obtained from the heat control means 32, etc., but it is obvious that the steam may be supplied from any suitable source.

Thermometric devices 48, 49, 50, 51, 52 and 53 are preferably employed for determining and regulating the more desirable temperatures at cracking chamber 16, hot air pipe 27, mixing chamber 20, igniting chamber 29, heat control means 32, etc., and at pipe 37, respectively. These temperature regulators may be of any suitable or approved design. They may also be introduced elsewhere, as needed.

Connected with the pipe 37 is a preliminary condenser 55, said pipe being controlled by valve 54. This preliminary condenser preferably discharges the condensed vapor and air mixture,—all of which is not condensed at this point—into a receiver 56, which is provided with taps 57, 58 for discharging recovered oil and water, respectively, or other products, the oil, of course, being at the higher level in said receiver. From the preliminary condenser 55 the remaining portions of the mixture are conducted through a condensing device, preferably such as shown, described and claimed in my co-pending application, Serial No. 370,126, filed March 31, 1920. This second condenser comprises a "zig-zag" condensing tube 60 leading from the pipe 59 and surrounded by a cooling jacket 61 connected with water supply and discharge pipes 62, 63. The second condenser discharges by a pipe 64 into a second receiver 65 provided with taps 66, 67 for respectively discharging layers of recovered oil and water.

A branch pipe 70 is shown as leading from the pipe 64, ahead of the second receiver 65, and it may be controlled by a valve 71. Pipe 70 leads to a condensing pump 72 for forcing the condensed vapors or gas through a pipe 74, a cooling coil 75 and a cooling device 73. From the coil 75 there leads a pipe 76 to a

third receiver 76^a for the condensate, and from this leads a pipe 76^b, to the pipe 81, with which it connects at a point adjacent the pipe 68, said pipe 76 being controlled by a valve 78. The drawings show only a simple condenser, yet it is clear that the invention is not limited to the use of water in the cooling jacket at ordinary temperatures, but also cold solutions may be used; and of course, all the usual accessories of condensing devices may be used to assist in the condensation of any products produced. The more volatile gases and vapors, as, for instance, acetic and formic aldehyde would be condensed by the by-pass condensing system 70 to 76, especially in the troublesome condensation temperatures of warm weather.

From the second receiver 65 there leads a pipe 68 provided with a valve 69, and this pipe leads, through the leg 81, to the fog and tar arrester 80. These last named parts are shown in Fig. 2, and the other parts therein shown will now be described. In passing, it is stated that good results in the fog arrester have been obtained by a filling of such material as wire cloth in strips, bundles and rolls, and other forms of metal, such as metal excelsior, and, indeed, common excelsior. It is clear that, as the destruction and absorption of the tar, oil or gas fog is a surface matter, the fog arrester will work much better as soon as the surfaces therein become slightly saturated with the very materials they are absorbing. I do not limit myself to this, but use also such precipitation as the Cottrell, or the like.

From the fog arrester there leads a pipe 82 for carrying off the remaining vapors which may be condensed or treated for the production of other materials. This pipe 82 leads to an absorber 83, provided with an inner "flanged spiral" 84, and this absorber is preferably of the type shown, described and claimed in my co-pending application Serial No. 365,271, filed March 12, 1920. The said absorber is for the purpose of recovering the vapor of the aldehydes, at least. From the absorber 83 there leads a pipe 85 to a second absorber 86 containing a "flanged spiral" 87, and arranged, constructed and operated preferably as disclosed by said application, Serial No. 365,271. In the second absorber sulphuric acid is preferably employed for use in the recovery of "unsaturated" hydrocarbon compounds leading to the alcohols. The sulphuric acid absorber 86 is provided with a discharge pipe 88 for the remaining vapors, and this pipe discharges into a third absorber 89, preferably provided with a spiral 90 and, constructed in accordance with said application, Serial No. 365,271. In this absorber 89 specific compounds are recovered from the unknown gases group. Leading from the third absorber 89 is a pipe 91 of any desired length so as to supply the remaining

tail gas at an adjacent point or some remote point. This tail gas is suitable for making good carbon black by suitable burning and collection, and to that end the pipe 91 may be 6 provided with burners 92 for depositing the carbon black upon collecting surfaces 93, from which the same may be removed and saved.

Among the many curious aspects and 10 phases of the many-sided reactions involved and implied in this apparatus and process, one of the most interesting is the curious trickery which mother nature uses and which must be anticipated and provided for. For 15 instance, it frequently happens that using measured quantities of oil, for instance, at the start, with a tight apparatus with no leaks, some of the products which must be produced seem almost at times to disappear 20 before one's eyes. Thus, the aldehydes which are produced in considerable quantities are not all in the steam water or oxidation water in receivers 56 and 65, nor are they all in the fog arresters or the water-absorption bottles, 25 but they must be somewhere; and it was found that the condensed "recovered" oil found in receivers 56 and 65 and in the fog arresters was itself a rich solution or emulsion of absorbed aldehyde compounds. These 30 absorbed aldehyde compounds can be shaken out from this oil by a generous quantum of water in which the aldehydes dissolve readily, This observation involves many new possibilities in the production and use of varnishes, 35 paints, inks and the like.

In connection with the cracking step of the process herein described, at times more or less hydrogen seems to be produced; and some 40 of this hydrogen may appear in the final tail gas, or it may be absorbed at certain places, as by adding itself to some of the "unsaturated" hydrocarbons; and this possibility must be considered in explaining the "O₂" 45 reaction, whereby derivatives may be obtained not merely of "unsaturated" compounds, but of "saturated" compounds.

Also, in this connection it should be noted that while we usually consider—in a broad qualitative sense—that water is neither an 50 oxidizer or reducer, but is a sort of "chemical bank of exchange", receiving and imparting both oxidizing and reducing actions; and, inasmuch as it is possible that water may add itself to the "unsaturated" hydrocarbons, 55 such as ethylene C₂H₄,—producing ethyl hydroxide, C₂H₅O—herein we have a curious case, where water is acting as though it were an oxidizer,—the real action, of course, involved must be referred to the nature and 60 action of the "unsaturated" ethylene;—and this is an illustration of many other related cases, both known and unknown.

Regarding the use herein of the terms "ignition", "igniter", or the like, of course it 65 is obvious that what is meant is not ignition

in the proper sense of burning with a visible flame, but rather, such a modified hidden burning or oxidation within the igniter 29 as will meet the demands implied in the apparatus, process and results. Of course, 70 open visible ignition which is attended with visible flame, almost invariably means rather extreme oxidation with a production of CO₂ and other waste products which are not primarily intended or desired.

It is obvious that there are two possibilities for the addition of water or steam to "unsaturated" molecules. One of these is where the steam is added directly to the "unsaturated" molecule shortly after cracking, and 80 would result in a combined oxidation-reduction addition product which might change the "unsaturated" compound into a corresponding "saturated" alcohol; for instance, ethylene plus water equals ethyl hydroxide. Another 85 kind of hydration may be illustrated in the subsequent treatment of the "unsaturated" hydrocarbons caught in the sulphuric acid absorber whereby ethyl sulphate is changed into sulphuric acid and alcohol. And either 90 or both of these reactions and results may occur in the same cycle, but in different parts of this apparatus and process.

Referring to Fig. 3, a modification is shown 95 in which the heat control means 32, etc, herein described are omitted. In this modification the supply of the desirable steam to the vapors or gas preliminary to ignition may be obtained from an independent source of steam, as through a pipe 94, or through the 100 medium of any suitable superheater, such as 95, for the purpose of supplying superheated steam. It will be noticed that in this modification the igniter 29 is connected directly with the preliminary condenser 55, as it may 105 be found that in some cases proper regulation and control may be obtained without the introduction of heat control means, such as 32, etc. This is but one of the many possible modifications to which the present apparatus 110 and process are susceptible, and it is to be understood that I do not limit myself in any way except as may be defined in the appended claims.

What I claim as new is:

1. The continuous process of making by-products from inactive and inert oil or gas, which consists in cracking such oil or gas and thereby vaporizing and rendering the hydrocarbon constituents more active and capable 120 of oxidation, preheating oxidizing gas by heat from the cracking, and then partially oxidizing the hydrocarbon constituents with such preheated gas.

2. The continuous process of making by-products from inactive and inert oil or gas, which consists in cracking such oil or gas and thereby vaporizing and rendering the hydrocarbon constituents more active and capable 125 of oxidation, mixing preheated oxygen with 130

the vaporized hydrocarbons while they are still heated as a result of the cracking, and then partially oxidizing the heated vapors in a separate chamber.

with heat-regulating surfaces cooled by a liquid, said steam being supplied by said liquid. 15

4. The continuous process of making by-products from inactive and inert oil or gas, which consists in cracking such oil or gas and thereby vaporizing and rendering the hydro-carbon constituents more active and capable 20 of oxidation, igniting the constituents for the recovery of the by-products, and passing the partially oxidized products in a countercurrent to a body of liquid which regulates the temperature of said products.

CHARLES S. PALMER.

5. The continuous process of making by-products from inactive and inert oil or gas, which consists in cracking such oil or gas and thereby vaporizing and rendering the hydro-carbon constituents more active and capable 10 of oxidation, mingling steam with said constituents, partially igniting the constituents for the recovery of the by-products, and passing the partially oxidized products in contact
